UNITED STATES PATENT OFFICE.

LEVI E. ENGEL, OF ELBE, WASHINGTON.

VEHICLE JACK.

Application filed August 2, 1926. Serial No. 126,489.

My invention relates to vehicle jacks and consists of a jack having two centrally pivoted horizontal bars insertible at one end under the vehicle to be lifted, and provided 5 at their other end with means for separating the bars.

The object of my invention is the production of an efficient jack of simple and cheap construction, and one which is particularly 10 adapted to being inserted under a rather extended projecting body or load. Another object is to produce a jack in which the operation of the lever, whether upwardly or downwardly, produces a lifting effect. Further objects will be disclosed by study of the 15 following specification.

The accompanying drawings illustrate a preferred embodiment of my invention.

Figure 1 is a side view of the jack shown 20 applied beneath the axle of a car.

Figure 2 is a section taken on the line 2—2 of Figure 1.

Figure 3 is a section through the casing taken at about the left hand face of the 25 toothed pillar or post as shown in Figure 2, the direction of view being towards the left, or outwardly from the said post.

The type of jack upon which my invention is herein illustrated, is that shown in my 30 Patent No. 1,553,074, issued Sept. 8th, 1925. The present invention differs from that shown in the construction at the outer or operating end of the jack, and includes both the supporting dolly and the mounting of 35 the lower lever upon the said dolly. It also includes the mechanism mounted upon the notched or toothed pillar or post, by which the end of the other lifting lever is raised.

As the construction and operation of the 40 lifting levers 1 and 10 is the same as in said patent, a specific description of these is deemed unnecessary. These levers differ from those of said patent only in being bent slightly different at the ends which are connected with the toothed pillar or post 2.

The central lever 10 has two webs which 45 embrace the lower end of the pillar 2, to which it is connected by a pivot pin 20. This pin is supported in lugs 30 which depend from a frame 3, which frame also has a 50 guiding socket 31 closely embracing the pillar body. Under each end of the frame 3 is a caster wheel and frame, represented as a whole by 32. This construction as a whole 55 may be called a dolly. It permits free universal movement of this end of the jack. It

also permits dropping the opposite end of lever 10 between the sides of lever 1 so as to permit insertion of this end under a low axle.

The actuating or power lever 4 is inserted in or secured to what may be called a lever base 40, which as it has been illustrated, has two terminal webs or plates 41, which are separated to span the pillar or post 2, 60 and also accommodate the webs or side arms of the dogs.

The enclosing case or frame 5 has its upper end 50 and lower end 51 provided with aligned openings accommodating the toothed 70 pillar or supporting post 2. These ends are connected by plates 52 positioned outwardly of the side faces of the post 2, enough to freely accommodate the terminal plates 41 of the lever base and the side arms 61 of the 75 dogs.

The frame or casing 5, towards its lower end has exteriorly projecting lugs 53 which are engaged by side opening notches of the 80 two parts of lever 1. Sufficiently above the lug 53 at one side of the frame to accommodate lever 1 and to prevent disengagement, is a lug 54 in which is journaled the axis of 85 a dog shifting cam 7, which will be later referred to.

The dogs 6 in outline much resemble the letter U, upside down. The two flat side wings or arms 61 are connected at their upper ends by a horizontal bar 60, which 90 is the tooth engaging member. The outline 95 of the cooperating toothed post or pillar is shown by broken lines in Figure 3.

The dogs are pivoted to the side plates 41 of the lever base by complementary lugs and 100 sockets at 62. These are situated at points 95 so related to the pivot between the lever base and the casing or frame 5, that as the lever is oscillated up and down, the dogs will be given opposite vertical movements, one rising to engage the next tooth of the post 100 while the other supports the load. The dogs are yieldingly held towards the post, as by a cross-connecting spring 63. The pivoting of plates 41 of the lever base to the casing or frame, is by notches 42 in the plates and 105 lugs 54 on the frame.

Mounted for vertical adjustment upon or in the frame 5, is a dog-controlling cam plate 8. A spring 83 mounted upon a guide stem 82 tends to throw this plate downwardly or towards the tooth-engaging bars 60. This plate has cam inclines 81 upon its lower 110

outer corners, adapted to engage the cross bars 60 of the dogs to throw the dogs outwardly as they rise, thus preventing their engaging the teeth 21 during the upper portion of their range of vertical movement. In consequence of this, they will not engage a tooth 21 of the pillar 2, and the operation of the lever 4 will lower the casing 5 and the load.

10 To raise the casing 5 and the load, a cam disk 7 is placed so as to engage under a shoulder 80 of the dog-controlling plate 8. By turning this cam disk through the external handle 70 the dog-controlling plate 8 is raised so that it will not engage the dogs, thereby permitting their engaging the teeth of the pillar or post 2, and to raise the casing or frame 5.

For convenience in moving the jack 20 around I provide a handle 29 secured to the upper end of the post 2.

The pivots 62 of the dogs being positioned one at each side (horizontally) of the pivot

54 of the operating lever, both the upward and downward movement of the lever produces a lifting effect upon the load-carrying frame 5. There is therefore, no non-working movement in the lever 4.

What I claim as my invention is:

A vehicle jack comprising two centrally pivoted lifting levers extending in approximately a horizontal direction, a dolly frame having supporting wheels under its ends and depending lugs at each side of the center of its length and a post receiving hole and guide between said lugs, a toothed post extending upwardly through said guide, a pivot connecting said post and an end of one of the lifting levers with said lugs, and a progressive lifting means guided on the post and supporting the like end of the other lifting lever.

Signed at Mineral, Washington, this 26 day of July, 1926.

LEVI E. ENGEL.
